MANDREL

Jay Clair Moore, Fredonia, Pa.

Application January 5, 1951, Serial No. 204,643

4 Claims. (Cl. 51—168)

1

This invention relates to the class of machine tools and more particularly to an improved mandrel structure for grinding machines.

An object of this invention is the provision of a mandrel structure which is so constituted as to provide for variation in thickness of different grinding stones so as to maintain the front face of the stone at the same place.

Another object of this invention resides in the provision of a novel design of mandrel which makes the use of a combined nut and locking flange so as to eliminate any member which may hinder the passing of a wrench jar or other tool past the end of the mandrel.

Still further objects of the invention reside in the provision of a novel mandrel structure that is strong, durable, highly efficient in operation, simple in construction and manufacture, formed from a minimum number of parts, and which is adapted for easy and simple removal and replacement of grinding stones.

These, together with the various ancillary objects of the invention which will become apparent as the following description proceeds, are attained by this mandrel structure, a preferred embodiment of which has been illustrated in the accompanying drawings, by way of example only, wherein:

Figure 1 is an exploded sectional view of the invention;

Figure 2 is a sectional view showing the mandrel structure in its assembled relationship; and,

Figure 3 is an end elevational view of the invention.

With continuing reference to the accompanying drawings wherein like reference numerals designate similar parts throughout the various views, reference numeral 10 generally designates the mandrel structure comprising the present invention which includes a spindle 12 adapted to be rotated, which spindle has a threaded portion 14 which is left-hand threaded. An extension 16 is integrally formed with the spindle 12 and is right-hand threaded.

Threadedly secured on the spindle 12 is a nut 18 which is adapted to abut against a supporting flange generally indicated at 20, which consists of a disk 22 having an outer annular flange 24. The supporting flange 20 is positioned on the spindle 12.

The grinding stone 26 may be any suitable emery wheel, sandstone wheel, or the like, provided with a central aperture 28. The grindstone 26 is provided with a sharpened periphery as at 30. This grindstone is slidably placeable 32 attached thereto of smaller diameter than the

2 upon the cylindrical portion 32 of the combined locking nut and flange member generally indicated at 34 which includes a disk 36 integrally formed with the cylindrical portion 32, which disk is provided with an outer flange 38 at its periphery. The grinding stone may extend onto the threaded portion 14 of the mandrel 12 when the thickness of the stone is greater than the space 32. Accordingly, any thickness of standard stone may be used without any change in the flange 34. Suitable span arranged holes or apertures 40 are formed in the disk 36 for aiding in the removing or replacement of the member 34 in threaded engagement on the extension 16. It is to be noted that the extension 16 is of less diameter than the rest of the spindle 12 and hence, forms a shoulder generally indicated at 42.

When placing the grinding stone on the spindle the nut 18 is backed off and the supporting flange 20 is also backed off to enable the stone to be readily placed on the spindle. Then, the stone having been placed on the cylindrical portion 32 of the member 34, the member 34 is threadedly secured on the extension 16 until the cylindrical portion 32 abuts against the shoulder 42. Then, the stone is forced out against the outside flange 38 by the nut 18 urging the member 20 against the stone with the flange 24 in intimate engagement therewith.

30 To remove the grinding stone, it is first necessary to loosen the nut 18. The member 34 should not be loosened until the nut 18 is first loosened.

Since the variation for thickness of the stone 36 is taken care of by the nut 18, then the front face of the stone will always be in the same position.

Since, from the foregoing, the construction and advantages of this mandrel structure are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but also the modifications and improvements may be readily resorted to which fall within the scope of the appended claims.

Having described the invention, what is claimed as new is:

1. A mandrel construction comprising a cylindrical spindle, said spindle having an extension 55 attached thereto of smaller diameter than the

spindle forming a shoulder, said spindle being left-hand threaded, a nut threadedly secured on said spindle, a supporting flange member on said spindle, said extension being right-hand threaded, a grinder stone having a central opening therethrough, a locking member comprising a tubular internally threaded portion, and a disk integrally formed with said tubular portion, an annular flange formed on the periphery of the disk, said tubular portion being received in the opening in said grinder stone, said locking member being threadedly secured on said extension in abutting engagement with said shoulder, said nut locking said supporting flange in engagement with said stone, said disk being held so that the annular flange thereon engages said grinder stone.

2. A mandrel construction comprising a cylindrical spindle, said spindle having an extension attached thereto of smaller diameter than the spindle forming a shoulder, said spindle being left-hand threaded, a nut threadedly secured on said spindle, a supporting flange member on said spindle, said extension being right-hand threaded, a grinder stone having a central opening therethrough, a locking member comprising a tubular internally threaded portion, and a disk integrally formed with said tubular portion, an annular flange formed on the periphery of the disk, said tubular portion being received in the opening in said grinder stone, said locking member being threadedly secured on said extension in abutting engagement with said shoulder, said nut locking said supporting flange in engagement with said stone, said disk being held so that the annular flange thereon engages said grinder stone, said disk having a pair of apertures therethrough for reception of a tool for selectively fastening and removing said locking member in engagement with said grinder stone.

3. A mandrel construction comprising a cylindrical spindle, said spindle having an extension attached thereto of smaller diameter than the spindle forming a shoulder, said spindle being left-hand threaded, a nut threadedly secured on said spindle, a supporting flange member on said spindle, said extension being right-hand thread-

ed, a grinder stone having a central opening therethrough, a locking member comprising a tubular internally threaded portion, and a disk integrally formed with said tubular portion, an annular flange formed on the periphery of the disk, said tubular portion being received in the opening in said grinder stone, said locking member being threadedly secured on said extension in abutting engagement with said shoulder, said nut locking said supporting flange in engagement with said stone, said disk being held so that the annular flange thereon engages said grinder stone, said disk having a pair of apertures therethrough for reception of a tool for selectively fastening and removing said locking member in engagement with said grinder stone, said supporting flange including a disk portion having an annular flange integrally formed therewith, said last recited annular flange being held in engagement with said grinder stone.

4. A mandrel construction comprising a cylindrical spindle, said spindle having an extension attached thereto of smaller diameter than the spindle forming a shoulder, said spindle being left-hand threaded, a nut threadedly secured on said spindle, a supporting flange member on said spindle, said extension being right-hand threaded, a grinder stone having a central opening therethrough, a locking member comprising a tubular internally threaded portion, and a disk integrally formed with said tubular portion, an annular flange formed on the periphery of the disk, said tubular portion being received in the opening in said grinder stone, said locking member being threadedly secured on said extension in abutting engagement with said shoulder, said nut locking said supporting flange in engagement with said stone, said disk being held so that the annular flange thereon engages said grinder stone, said supporting flange including a disk portion having an annular flange integrally formed therewith, said last recited annular flange being held in engagement with said grinder stone.
